[57] CLAIM

The ornamental design for a wiener stick, as shown and described.

DESCRIPTION

FIG. 1 is a perspective view of a wiener stick showing my new design;

FIG. 2 is a top plan view thereof, the grip shown in an alternate position;

FIG. 3 is a bottom plan view of FIG. 2;

FIG. 4 is a left side elevation view of FIG. 2;

FIG. 5 is a right side elevation view of FIG. 2;

FIG. 6 is a front elevation view of FIG. 2; and,

FIG. 7 is a rear elevation view of FIG. 2.

The wieners are shown in broken lines for illustrative purposes only and form no part of the claimed design.
